Eaton's Marina Power marine product portfolio, Date Jan. 24, 2022 [online], [retrieved Dec. 17, 2024], <https://www.youtube.com/watch?v=JEo3z2NP67c> (Year: 2022).*Primary Examiner — Shawn T Gingrich*Assistant Examiner* — Anehita E. Oribabor(74) *Attorney, Agent, or Firm* — Peter J. Van Bergen(57) **CLAIM**

The ornamental design for a marina power pedestal, as shown and described.

DESCRIPTION

FIG. 1 is a first perspective view of a marina power pedestal in accordance with our new design;

FIG. 2 is a second perspective view thereof;

FIG. 3 is a top plan view thereof;

FIG. 4 is a bottom plan view thereof;

FIG. 5 is a back elevational view thereof;

FIG. 6 is a front elevational view thereof;

FIG. 7 is a left side elevational view thereof; and,

FIG. 8 is a right side elevational view thereof.

The broken lines in the figures depict unclaimed environment that are shown for illustrative purposes only, and form no part of the claimed design.
